VERN E. ALDEN, OF BALTIMORE, MARYLAND, ASSIGNOR TO THE BABCOCK & WILCOX COMPANY, OF BAYONNE, NEW JERSEY, A CORPORATION OF NEW JERSEY

SUPERHEAT-REGULATING DEVICE

Application filed May 29, 1925. Serial No. 33,721.

My present invention relates to superheaters provided with regulating devices by which the degree of superheat delivered from the superheater may be regulated. My invention will be best understood 5 from the following description and the annexed drawings, in which Fig. 1 is an outside view of a separately fired superheater, with some of the parts broken away and embodying an illustrative form of my invention; Fig. 10 Fig. 2 is an enlarged view, with some of the parts broken away, of a portion of Fig. 1, and Fig. 3 is an enlarged view of a portion of Fig. 1.

Like reference characters indicate like parts in the several views.

In the illustrative arrangement, I have shown a separately fired superheater having a casing 10 and banks of tubes 11, the tubes of these banks being inverted U-tubes connected to the lower drums 12 with a steam inlet pipe 13 connected to the rearmost drum 12 and the front bank of tubes 11 being connected to a superheater outlet pipe 14. The superheater is fired, in the illustrative form, by an under-feed stoker 15 and the casing 10 may also be provided with a steam generating apparatus in the form of a water tube boiler, the drum 16 indicating a portion of such a separate steam generating apparatus. Since such an apparatus, however, may be used or not, as desired, and is no part of my present invention, further description thereof will be unnecessary. The superheater which I have shown, is of a well known type, but I have shown it merely for purpose of illustration, since the specific form of superheater is no part of my present invention.

It will be understood that in the form of superheater illustrated, steam from one or more steam generators or from intermediate stages of a steam turbine or any other source, flows through the inlet pipe 13 and from thence through the tubes 11 and the drums 12 to the superheater outlet 14, such steam, which may be saturated steam when it enters the superheater, being raised to a high degree of superheat in its passage through the superheater.

As is well understood, the operating conditions in a power plant will vary from time

to time, so that without provision to that end, the superheat in the steam delivered through the pipe 14 will vary considerably, and this will cause serious operating difficulties, particularly if, as is usually the case, it is desired to maintain the superheat at as high a point as may be without exceeding a predetermined limit which would cause operating difficulties.

It has heretofore been proposed to regulate the superheat by injecting water into the steam after it has passed the superheater. This, however, presents a number of difficulties. For instance, where the superheated steam is supplied to turbines, it is particularly desirable that no water shall enter the turbines. When water is injected into the superheated steam between the superheater and the turbine, there is always the possibility that the water will not be entirely vaporized and that some water will pass into the turbine. This difficulty has heretofore been controlled largely by spraying the water into the steam, but obviously the maintenance of these sprays and the insurance that the spray will be fine enough to make certain the evaporation of all of the water adds to the operating difficulties.

In my present arrangement, I overcome these difficulties by admitting water to the steam entering the superheater in accordance with the operating conditions, so that the degree of superheat in the steam leaving the superheater can be maintained substantially constant. Furthermore, it will be obvious that by thus introducing the water, its evaporation will be insured as it is carried through the superheater, so that fine spraying of the water will not be necessary.

Preferably, I arranged my apparatus so that the amount of water admitted to the steam at the inlet side of the superheater will be in accordance with the temperature of the steam at the superheater outlet. In other words, if the superheat in the outlet tends to rise, than I admit water into the inlet side, and if the quantity thus admitted is not sufficient to bring the superheat down to the desired point, then a greater rate of flow of water is set up in the inlet side until the ad-

ditional quantity of water to be evaporated in the superheater will bring the degree of superheat at the outlet down to the desired point.

It is obvious that the admission of water may be done by hand and that gauges may be applied to the outlet 14 by which the operator will be guided in such admission. Preferably, however, I provide an automatic means for admitting the water to be controlled by devices located in the superheater outlet, so that the quantity of water admitted will be automatically determined by the conditions in this outlet.

As an illustrative form of such automatic arrangement, I have shown an apparatus which is described more in detail in the co-pending application of David S. Jacobus, Serial No. 748,885, filed November 10, 1924, but it will be understood that any other form of temperature controlled apparatus may be used for this automatic control.

In the arrangement described, a valve body 17 is provided with a plurality of ports 18, each having a valve 19 cooperating therewith, this valve body 17 being located in a water supply pipe 20 having its outlet 21 entering the upper part of a vertical portion 22 of the superheater inlet pipe, this pipe preferably being provided with a long bend between the vertical portion and the superheater drum 12. The pipe 20 may be provided with a number of small openings in its lower portion so that water passing through the pipe 20 will fall downward in the vertical section 22. With my arrangement, however, it will be unnecessary to attempt to spray this water into fine drops.

In the vertical section 22 I have provided a plurality of water spreading devices in the form of screens held between the sections of the pipe, these screens serving to receive the water from the pipe 20 and spread it over a large surface, so that the incoming steam which is also flowing through these screens, will contact with the water spread over these expanded surfaces and take it up and carry it into the superheater. These screens also serve to prevent any foreign bodies from being carried into the superheater.

The specific form of water spreading device may be widely varied, the form shown being a pair of heavy wire screen sections 23 between which is held a mass 24 of small bodies which may be of any desired material. It will be understood that if the screening effect is not desired, then the water may be caused to flow down over any extended surfaces positioned in the pipe so as to be contacted by the inflowing steam.

The valves 19 may be operated independently and it will be obvious that in the arrangement of the valve body 17, as defined in Fig. 2, the amount of water which will flow from right to left through the valve body

will be determined by the number of valves 19 which are opened. While these valves 19 may be operated by hand, I prefer to operate them automatically, and in the arrangement shown, each valve 19 has a stem 25, to which is attached a soft iron core 26 moving in a solenoid 27. The valves are normally held closed by a spring 28, the height of the lift of the valves being controlled by the contact between the top of the core 26 and the bottom of a hollow body 30 surrounding the upper end of the stem 25 and whose position is controlled by a screw 29 connected to some fixed part.

In the superheater outlet pipe 14 is a receptacle 31 containing an expansible fluid which is connected through a pipe 32 to a vertical tube 33, in the walls of which are inserted electric contact points, the tube 33 being filled with mercury, the height of which, of course, will be determined by the temperature of the receptacle 31, which, in turn will be determined by the temperature of the steam leaving the superheater. There may be as many of the contacts as desired, each being in circuit with one of the solenoids 27 and a source of energy. It will be sufficient to describe one of these circuits, the contact member 34 of which is connected through the wire 35 with one of the solenoids 27, the other side of the solenoid being connected through the wire 36 with the wire 37, the battery 38, the wire 39 and a contact point 40 at the bottom of the tube 33. As the temperature of the steam in the outlet rises, the mercury column in the tube 33 will also rise and when it reaches the contact 34, a circuit is formed between the contacts 40 and 34 and the wiring connected thereto to open the valve connected with the solenoid 27 in that circuit.

It will be understood that in the illustrative form, the mercury in rising to the contact 34 will have successively risen to the lower contacts and will have therefore successively opened the valves 19 in circuit therewith, so that, in the illustrative form, when the mercury reaches the contact 34, all of the valves will have been opened.

Obviously, similarly, as the temperature in the superheated steam begins to drop, the mercury in the tube 33 will also drop and thus the valves 19 will be closed one at a time to shut off the water until the desired balance is reached.

In order to prevent disaster through failure of the water supplied through the pipe 21 to keep the superheat within the desired limits, in the arrangement shown, there is a contact 40' at the upper part of the tube 33 which, when the mercury reaches it, closes a circuit through an operating device for a water operated motor 41 to open doors 42 in the setting to permit air to pass directly into the setting to cool the superheater tubes 11. Such arrangement is no part of my present invention,

and further description thereof will be unnecessary.

It will be understood that the arrangement which I have shown is merely illustrative, and that the embodiment thereof may be widely varied.

While in the description and the appended claims, I have referred to the device to be regulated as a superheater, it will be understood that I include in that term any device in which steam out of contact with water is heated, such, for instance, as the now well-known reheaters for heating steam between stages in steam turbines and the like.

I claim:

1. In a superheat regulating device, a superheater, an inlet pipe therefor, means to admit water into said inlet pipe, and water spreading devices in said inlet pipe between the superheater and the point of admission of the water, whereby the water is spread over surfaces contacted by the steam before entering the superheater.

2. In a superheat regulating device, a superheater, an inlet pipe therefor, means to admit water into said inlet pipe, said pipe having a vertical portion, and water spreading devices in said vertical portion between the superheater and the point of admission of the water, whereby the water is spread over surfaces contacted by the steam before entering the superheater.

3. In a superheat regulating device, a superheater, an inlet pipe therefor, means to admit water into said inlet pipe, said pipe having a vertical portion into the upper part of which the water is admitted, and water spreading devices in said vertical portion and positioned to receive the water so admitted and to be contacted by the steam flowing to said superheater.

4. In a superheat regulating device, a superheater, an inlet pipe therefor, means to admit water into said inlet pipe, said pipe having a vertical portion into the upper part of which the water is admitted, and a screen in said vertical portion and positioned to receive the water so admitted and adapted to permit the steam flowing to said superheater to flow therethrough.

5. In a superheat regulating device, a superheater, an inlet pipe therefor, means to admit water into said inlet pipe in relatively large masses, and water spreading devices in said inlet pipe between the superheater and the point of admission of the water to spread such masses over an extended surface contacted by the steam flowing to the superheater.

6. In a superheat regulating device, a superheater, an inlet pipe therefor, means to admit water into said inlet pipe in relatively large masses, said pipe having a vertical portion, and a screen in said vertical portion beneath the point of admission of the

masses of water and positioned to receive the same and to permit the steam flowing to the superheater to pass through the same and contact with the water therein.

7. In a superheat regulating device, a superheater having an inlet and an outlet, means to admit water into said inlet comprising a water delivery pipe, a water supply pipe and a multiple-ported valve body connecting the two pipes, each port having a separately-openable valve therefor, and means for opening said valves successively.

8. In a superheat regulating device for a superheater having an inlet and an outlet, means to admit water into said inlet, comprising a water delivery pipe, a water supply pipe and a multiple-ported valve body connecting the two pipes, each port having a separately-openable valve therefor, a thermostat in said outlet and means operated by said thermostat to open successively said valves as the temperature of the superheated steam at said outlet increases.

9. In a superheat regulating device for a superheater having an inlet and an outlet, means to admit water into said inlet, comprising a water delivery pipe, a water supply pipe and a multiple-ported valve body connecting the two pipes, each port having a separately-openable valve therefor, and a thermostat in said outlet, solenoids to open each of said valves, and electric circuits each containing one of said solenoids and arranged to be energized successively by said thermostat.

10. In a superheat regulating device for a superheater having an inlet and an outlet, means to admit water to said inlet, a thermostat in said outlet, electric circuits for operating successively water-admitting means and controlled by said thermostat, whereby the quantity of water admitted is increased as said electric circuits are successively operated.

11. In a superheat regulating device, a superheater having an inlet and an outlet, a pipe adapted to discharge water into said inlet, a plurality of valves controlling the discharge of said water and means to operate the valves successively upon changes in the heat of the steam in said outlet.
